UNITED STATES PATENT OFFICE

FRANK C. LA MAR, OF NEW YORK, N. Y., ASSIGNOR TO GREAT WESTERN FUSE COMPANY, OF PITTSBURGH, PENNSYLVANIA, A CORPORATION OF DELAWARE

RENEWABLE FUSE

Application filed March 23, 1928. Serial No. 264,138.

The object which I have in view is the provision of a new and improved renewable fuse which is of simple and inexpensive, yet durable construction, which may be easily assembled and disassembled without requiring skill, and which will be safe and efficient in service.

In the accompanying drawings, wherein I have illustrated the best embodiments of the principles of my invention now known to me, Fig. 1 is a longitudinal section of the fuse.

Fig. 2 is a broken elevation showing one end of the fuse with the screw cap removed.

Fig. 3 is an end view of the same end of the fuse with the screw cap removed.

Fig. 4 is an inner face view of the slotted washer.

Fig. 5 is an elevation showing the two terminal blades connected by the fusible link, the closure disk fixedly mounted on one blade and the slotted washer and dowel applied to the other blade.

Fig. 6 is an elevation of the left hand terminal blade in Fig. 1.

Fig. 7 is an end view of one of the ferrules.

Fig. 8 is a detail showing the dowel-pin.

Referring to the drawings, 1 represents the cylindrical shell which may be of insulating material, such as fibre.

30 A metal ferrule 2 is fixed on each end of the shell 1 as by threaded engagement and riveting. The shell and ferrules comprise the tubular body of the fuse.

The ferrules 2 are provided at their ends 35 with recesses 3 which form seats and which are preferably in diametrically opposed pairs.

4 and 5 are the metallic terminal blades having reduced inner ends to which are detachably secured the ends of the fusible link 6.

One of the terminal blades, the right hand blade 4 in Fig. 1, has fixedly mounted thereon the metal circular closure head 7 which is arranged to fit on the end of the corresponding ferrule 2. The head 7 is provided with a diametrically disposed rib 8 on its inner face whose ends engage the seats 3 to prevent relative rotation between the head and the fuse body.

50 An annular screw cap 9 is screwed onto ex-

ternal threads on the ferrule to clamp the head fixedly in position relative to the fuse body.

The other blade 5 is provided with a fixed abutment or plate 10 which when the fuse is 55 assembled lies slightly within the outer end of the corresponding ferrule 2.

11 represents a slotted washer which slips down over the end of the blade 5 and fits against the end of the ferrule 2. The inner 60 face of the washer 11 is provided with arcuate shoulders 12 which fit down into the end of the ferrule and also with diametrically opposed lugs 13 which engage the seats 3 in the end of the corresponding ferrule 2. When 65 in place the slotted washer engages the abutment 10 of the blade 5.

The blade 5 is also provided with a transversely disposed hole 14 in which is driven the dowel-pin 15 to hold the washer 11 in 70 place against the abutment 10 of the blade 5.

I prefer to give the hole 14 a taper from one end to the other and to taper the dowel pin 15 so as to impart an inwardly exerted wedging action on the washer 11 to force it 75 into snug engagement with the abutment 10 and thus seal the edges of the slot in the washer 11 against the outward escape of flame along the blade.

The parts are clamped rigidly in position 80 by means of the annular screw cap 9 which is screwed onto the exterior threads of the ferrule 2.

The cap also prevents the dislodgment of the dowel pin by longitudinal movement 85 thereof.

To assemble the fuse, the assembled terminal blades and fusible link are inserted into the fuse body from the right end in Fig. 1 until the closure head 7 of the blade 4 rests 90 against the end of the ferrule with its rib 8 engaging the ferrule seats 3. The corresponding screw cap 9 is then applied and tightened. The slotted washer 11 is then slipped down over the other blade 5 until its 95 lugs 13 engage the seats 3 in the end of the ferrule 2.

The dowel 15 is then driven into the hole 14 to tighten the slotted washer 11 against the abutment 10 of the blade 5, and the corre- 100

sponding screw cap 9 is then screwed onto the ferrule to hold the parts against relative movement.

To disassemble the fuse the screw cap 9 on 5 the left end of the fuse in Fig. 1 is first removed, the dowel is driven out and the slotted washer slipped off the end of the blade 5.

The other screw cap is then removed and 10 the blade 4 and the parts attached thereto may then be lifted off.

It is evident from the foregoing that my 15 renewable fuse is extremely simple in construction, comprising a minimum number of separate parts. It is thus inexpensive to manufacture.

It is easily and quickly assembled and dis- 20 assembled without requiring skill or special tools.

Furthermore it is efficient, as the fusion of 25 the fusible link is not attended by the outward travel of flames along the blade, because the slotted washer 11 is wedged and clamped down snugly onto the abutment 10 which seals the edges of the slot in the washer.

What I desire to claim is:—

1. In a renewable fuse, the combination of 30 a tubular body formed of insulating material, a metal ferrule fixed on the end of said body and provided with a pair of diametri- 35 cally opposed notches in its outer end, said ferrule also having screw threads on its outer surface, a blade terminal having a fixed abutment adjacent to its inner end and arranged 40 to have the fusible link detachably connected to its inner end, said blade being also pro- 45 vided with a transversely extending hole, a washer provided with a transversely disposed slotted opening closed at both ends and ar- 50 ranged to be slid down over the blade and to 55 rest against the end of the ferrule, said washer being provided with a rib to engage said notches to prevent relative rotative move- 60 ment between the body and the terminal, a 65 pin driven through said hole to secure said washer in place, and an annular cap screwed down onto said ferrule and having an in- 70 wardly extending annular flange arranged to bear on said slotted washer.

2. In a renewable fuse, the combination of 75 a tubular body formed of insulating material, a metal ferrule fixed on the end of said body and provided with a pair of diametri- 80 cally opposed notches in its outer end, said ferrule also having screw threads on its outer surface, a blade terminal having a fixed abutment adjacent to its inner end and arranged 85 to have the fusible link detachably connected to its inner end, said blade being also provided 90 with a transversely extending hole tapering 95 from one end to the other, a washer provided 100 with a transversely disposed slotted opening closed at both ends and arranged to be 105 slid down over the blade and to rest against 110 the end of the ferrule, said washer being pro-

vided with a rib to engage said notches to prevent relative rotative movement between the body and the terminal, a wedge-pin driven through said hole to secure said washer in place, and an annular cap screwed down onto 70 said ferrule and having an inwardly extending annular flange arranged to bear on said slotted washer.

Signed at New York, N. Y., this 19th day 75 of March, 1928.

FRANK C. LA MAR.
